UNITED STATES PATENT OFFICE.

JOHN H. DEMPSEY, OF CLEVELAND, OHIO.

ARCH BRICK.

Application filed February 18, 1920. Serial No. 359,490.

To all whom it may concern:

Be it known that I, JOHN H. DEMPSEY, a citizen of the United States, and a resident of the city of Cleveland, in the county of 5 Cuyahoga and State of Ohio, have invented a new and Improved Arch Brick, of which the following is a full, clear, and exact description.

This invention relates to improvements 10 in arch bricks, an object of the invention being to provide a refractory brick or tile which is supported upon the arch tubes of a boiler fire-box, to form an arch, to control or direct the flow of smoke and gases 15 through the boiler.

A further object is to provide an improved 20 construction or shape of brick which cooperates with adjacent bricks to snugly fit the arch tubes and the side of the fire-box, which permit of easy adjustment without undue binding, and which embody structural strength by reason of the curved or arched shape of the respective bricks.

A further object is to provide an improved 25 construction of brick which, when assembled on the arch tubes, present a smooth surface or wall to the fire-box side and each brick is curved or arched transversely on its outer face imparting the maximum of 30 strength and durability thereto.

With these and other objects in view, the invention consists in certain novel features of construction and combinations or arrangements of parts, as will be more fully 35 hereinafter described and pointed out in the claims.

In the accompanying drawings—

Figure 1 is a view in longitudinal section 40 of a locomotive with the improved bricks placed on the arch tubes therein.

Figure 2 is a fragmentary plan view of my improved brick arch.

Figure 3 is a view in section on the line 3—3 in Figure 2.

Figure 4 is a plan view of one of the bricks.

Figure 5 is a view in side elevation of Figure 4.

Figure 6 is a view in section on the line 50 6—6 of Figure 4.

Figure 7 is a view in section on the line 7—7 of Figure 4 showing two bricks in position.

Figure 8 is a plan view illustrating a 55 modified form of brick.

1 represents a steam boiler of the locomotive type having a fire-box 2 with arch tubes 3 extending longitudinally of the fire-box as is customary in the art.

On these arch tubes 3 by improved bricks 4 are supported. The bricks 4 are of refractory material and are commonly known in the art as blocks, tile, or brick, and I shall use the term "brick" as a preferable term to define the device.

Referring particularly to Figures 4, 5, 6 and 7, it will be noted that the brick 4 has a flat lower surface 5 and a curved or arched upper face 6, the arch being transversely of the brick. The longitudinal edges 70 of the brick are curved transversely as shown at 7 to conform to and to fit the arch tubes 3, and these curved faces 7 permit the relatively sharp edges of the bricks to come together as shown in Figure 7, to prevent 75 binding action and yet allow of flexibility of adjustment to properly position the bricks on the tubes. The curved edges 7 of the bricks 4 are in reality the inner surfaces of longitudinal grooves, so that the lower surfaces 5 of the bricks are positioned between the boiler tubes, and all of these surfaces 5 are in substantial alignment so that a smooth flat surface is presented to the fire, while the upper surfaces of the bricks are arched 80 as shown at 6 to give the maximum strength and durability to the brick.

The brick 4 is provided centrally with an opening 8 and in its ends with recesses 9 so that the bricks when assembled, form a 90 series of openings in their longitudinal centers, to allow for the passage of smoke and gases through the arch. In the sides of the brick 4 curved recesses 10 are provided which permit a flow of smoke and gases in 95 contact with the tubes 3 as illustrated clearly in Figure 7. These recesses 10 may be staggered along the longitudinal edges of the bricks as indicated, or they may be otherwise arranged in accordance with the desire 100 of the user. These several openings in the bricks not only allow gases to pass through but also serve the purpose of checkering or subdividing the swirling gases in their passage.

At the sides of the fire-box it is necessary to provide half bricks 11 which are formed by splitting the bricks 4 longitudinally, and it will be noted, particularly by reference to Figures 2 and 3, that these half bricks 110

11 fit snugly against the sides of the fire-box and maintain the general contour of the arch.

In the modification illustrated in Figure 5 8, I show a longitudinal series of openings 12 in the brick 13, which in other respects is similar to the brick 4 above described.

The purpose of the holes in the tiles or bricks is to checker or mix more scientifically 10 the uncombusted gases, smoke and air; also in this checkering operation in passing through the holes greatly increased radiation surface is passed over, which when the bricks are heated, accentuates the process 15 of combustion.

It will be noted if the smoke, gases, etc., merely passed over the flat inner side or face of the bricks when heated, there would be the loss of checkering mentioned in passing through the holes.

Various slight changes may be made in the general form and arrangement of parts described without departing from the invention, and hence I do not limit myself to 25 the precise details set forth, but consider myself at liberty to make such changes and

alterations as fairly fall within the spirit and scope of the appended claims.

I claim:

1. A brick of the character described, having a flat lower face and a transversely arched upper face, said brick having grooves in its longitudinal edges and having a central opening, and recesses in its ends, and said brick having transversely curved recessed portions adjacent its ends at its opposite sides.

2. The combination with a boiler fire-box, and arch tubes therein, of an arch supported on the tubes and composed of a series of independent refractory bricks, said bricks having longitudinal grooves receiving the arch tubes and resting thereon, said bricks having flat lower faces and transversely arched upper faces, said bricks having openings therein and having recessed edges, whereby passages are provided through the bricks for the smoke and gases and the smoke and gases caused to contact with the boiler tubes, and half bricks located adjacent the walls of the fire-box.

JOHN H. DEMPSEY.
